UNITED STATES PATENT OFFICE

JAMES S. REID, OF CLEVELAND, OHIO, ASSIGNOR TO THE EATON AXLE & SPRING COMPANY, OF CLEVELAND, OHIO, A CORPORATION OF OHIO

CLOSURE

Application filed June 12, 1929. Serial No. 370,379.

This invention relates to closure devices, such as are used in connection with fuel tanks and radiators of motor vehicles and the like. More particularly the invention relates to a cap or closure member adapted for locking engagement with a tubular member upon relative rotation of said members.

The object of this invention is to provide an improved form of closure in which the means securing the locking member to the body of the closure is provided with a vent passage; and in which means is provided for automatically closing said vent passage.

The invention may be further briefly summarized as consisting in certain novel combinations and arrangements of parts herein-after described and set out in the appended claims.

In the accompanying sheet of drawings forming a part of this application—

Fig. 1 is a sectional elevation of the closure device of my invention showing the cap member applied to the tubular member;

Fig. 2 is a bottom plan view of the cap member;

Fig. 3 is a sectional view taken on line 3—3 of Fig. 1;

Fig. 4 is a sectional view taken on line 4—4 of Fig. 3;

Fig. 5 is a fragmentary elevational view showing the extension member;

Fig. 6 is a top plan view of the tubular member; and

Fig. 7 is a sectional view of the tubular member taken on line 7—7 of Fig. 6.

Referring now to the drawings for a detailed description of my invention, I show my closure device as comprising a cap member 10 applied to a filling tube or neck member 11.

This tubular member may be an integral part of a container such as a fuel tank radiator or the like, or, as shown in the drawings, may be provided with a base flange 12 by means of which the neck may be secured to

the wall 13 of a container in any suitable manner. The tubular member is provided at its outer end with a laterally extending flange 14, which is adapted to form a gasket seat and which is provided with recesses or openings 15 and depending flanges 16. The de-

pending flanges 16 are shaped and arranged to form the cam portions 17 which terminate in the dwell portions 18 and the abutments 19.

The cap member or closure 10 of my closure device is adapted for releasable locking engagement with the tubular member upon rotation of said cap member relative to the tubular member. The body portion of this cap member comprises a top part 20 and a bottom part 21. The metal of the outer edge portion of the bottom part is bent upon itself to form a reinforcing bead 22 which is engaged by the annular portion 23 of the top part to rigidly and permanently secure said parts together.

For releasably retaining the cap member or closure 10 on the tubular member 11 I provide a locking member 24 having resilient fingers 25 which are adapted to enter the recesses 15 of the tubular member when the closure is applied to the tubular member. Upon rotation of the closure the fingers engage the cam portions 17 and dwell portions 18 and bear against the abutments 19.

The locking member 24 is carried by the boss 26 which is formed centrally of the bottom part 18. As clearly shown in Fig. 3, portions of the bottom wall of the boss 26 are depressed to form the spaced lugs 27. These lugs serve as a retaining means for preventing the locking member from moving laterally relative to the boss, and in addition these lugs facilitate the proper positioning of the locking member during the assembling of the parts. As a convenient means for securing the locking member 24 to the bottom part 18 I provide a rivet 28 which extends through the locking member and through the bottom wall of the boss 26.

The rivet 28 is provided with a passage 29 therethrough which serves as a vent passage for admitting air to the container to prevent a vacuum from forming therein as fluid is withdrawn from the container. To prevent fluid from escaping through the vent passage 29, when the contents of the container is splashed about, I provide a valve 30. This valve is made light in construction so that when the contents of the container, to which

the cap member has been applied, is splashed about the valve will be moved upwardly to close the vent opening and thus prevent the escape of any of the contents. The valve 5 consists of a disc member 31, preferably of flexible material, such as leather, and a headed valve pin or stem 32 which passes through the valve disc and extends through the vent passage 29. The upper end of the valve pin 32 is bent as indicated at 33 to loosely retain the 10 valve in place.

A cup shaped extension member 34 is preferably provided for engagement with the boss 26 and is permanently secured thereto by 15 means of the rivet 28. The side wall of this extension member is provided with aligned openings 35 through which the resilient fingers 25 project. The extension member serves as a means for facilitating the centering of 20 the cap member when the same is applied to the tubular member, and also serves as a housing which protects the locking member from damage.

The bottom part 18 of the cap member is 25 provided with a continuous axially extending rib 36 which aligns with the flange 14 of the tubular member, when the cap member is secured in position, and engages the gasket 37 interposed between the cap member and 30 the tubular member to form an effective seal. Vent openings 38 are provided in the bottom part 18 of the cap member, and if desired a central opening 39 may be provided in the top part 17. These openings serve as vent 35 passages leading to atmosphere from the space between the top and bottom parts forming the body portion of the cap member.

While I have shown and described the device of my invention in a detailed manner, 40 it should be understood, however, that I do not limit myself to the precise details shown and described, but regard my invention as including such changes and modifications as 45 do not involve a departure from the spirit of my invention and the scope of the appended claims:

1. A closure comprising a top part, a bottom part retained in said top part, a locking member, means for securing said locking member to said bottom part, said securing means having a vent passage therethrough, and means for automatically closing said 115 vent passage.

2. A closure comprising a top part, a bottom part held in said top part, a locking member having resilient fingers, an extension member having openings through which said fingers project, means for securing said extension member and said locking member to said bottom part, said securing means having a vent passage therethrough, and means for automatically closing said vent passage.

3. A closure comprising a top part, a bottom part held in said top part and having a central boss, an extension member depending

from said boss, a locking member disposed in said extension member and having resilient fingers extending through openings in the wall of said extension member, and means for securing said extension member and said locking member to said central boss, said securing means having a vent passage therethrough.

4. A closure comprising a top part, a bottom part held in said top part and having a central boss, an extension member depending from said boss, a locking member disposed in said extension member and having resilient fingers extending through openings in the wall of said extension member, means 80 for securing said extension member and said locking member to said central boss, said securing means having a vent passage therethrough, and means for automatically closing said vent passage. 85

5. A closure comprising a top part, a bottom part retained in said top part, a locking member, means securing said locking member to said bottom part, said securing means having a vent passage therethrough, 90 and valve means for automatically closing said passage comprising a disk adapted to be pressed against the inner end of said securing means.

6. A closure comprising a top part, a bottom part retained in said top part, a locking member, means securing said locking member to said bottom part, said securing means having a vent passage therethrough, and valve means for automatically closing said 100 passage comprising a disk, means extending through said passage for loosely suspending said disk adjacent the lower end of said connecting means whereby liquid splashed against said disk will press the same against 105 said lower end.

In testimony whereof, I hereunto affix my signature.

JAMES S. REID.
